(57) **CLAIM**

The ornamental design for a TV receiver, as shown and described.

DESCRIPTION

FIG. 1 is a front, right side, perspective view of a TV receiver showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion of the claimed design shown within the area designated as 9 in FIG. 1 thereof;

FIG. 10 is a front, right side perspective view with environmental subject matter showing in a partially exposed configuration; and,

FIG. 11 is a front, right side perspective view of the TV receiver shown in a fully exposed configuration.

The dot-dash broken lines indicate where the enlargements have been taken, and form no part of the claimed design. The

(Continued)

dash-dash broken lines indicate portions of the TV receiver that form no part of the claimed design.
